United States Patent

Des. 242,293
Patented Nov. 9, 1976

242,293

TEETHER

Richard L. Panicci, Hanover, Mass., assignor to
Kiddie Products, Inc.

Filed Apr. 21, 1975, Ser. No. 570,004

Term of patent 14 years

Int. Cl. D24—04

U.S. Cl. D83—8 C

FIG. 1

FIG. 2

FIG. 3

FIG. 4

FIG. 5

FIG. 6

FIG. 7

FIG. 8

FIG. 9

FIG. 1 is a perspective view of a teether showing my new design;

FIG. 2 is a top plan view thereof;

FIG. 3 is a side elevation thereof;

FIG. 4 is a top plan view of a second modified embodiment of the teether illustrated in FIG. 1;

FIG. 5 is a side elevation thereof;

FIG. 6 is a perspective view of a third modified embodiment of the teether illustrated in FIG. 1;

FIG. 7 is a cross section take on line 7—7 of FIG. 6;

FIG. 8 is a top plan view of a fourth modified embodiment of the teether illustrated in FIG. 1; and

FIG. 9 is a side elevation thereof.

I claim:

The ornamental design for a teether, as shown and described.
